UNITED STATES PATENT OFFICE.

CHARLES P. JACOBS, OF INDIANAPOLIS, INDIANA.

COMBINED BOUQUET-HOLDER AND BADGE-PIN.

SPECIFICATION forming part of Letters Patent No. 268,901, dated December 12, 1882.

Application filed July 21, 1882. (No model.)

To all whom it may concern:

Be it known that I, CHARLES P. JACOBS, of Indianapolis, Marion county, Indiana, have invented a new and useful Improvement in 5 Combined Bouquet-Holder and Badge-Pin, and other ornaments worn upon the clothing, of which the following is a description, reference being made to the accompanying drawings, in which several styles of such pins are 10 shown.

Figure 1 represents one style, consisting of a flat top bar, to the under side of which is attached a circular piece having points and a clasp-piu and eye of the ordinary kind. Fig. 15 2 is a longitudinal section of the same. This style is well adapted for holding bouquets, the stems of the flowers being placed under the curved piece, and the piu being passed through 20 the garment, the bouquet is held firmly in place, the points passing into the stems. Fig. 3 represents another style, in which the curve to hold the bouquet is made in the upper part 25 of the pin. Either of these pius may be used without the points, but I preferably use them. Fig. 4 represents another style formed of a single wire, in which the loop to hold a bouquet or badge is formed of the wire itself.

I am aware that a pin has been made where- 30 in a circular socket has been attached to the plate or bar for holding a bouquet or badge,

as in Letters Patent granted Henry J. Rogers, July 16, 1872, and do not claim such a device. That device is different from mine, as the tubes are there pinched together to hold the stem, while in mine the clothing to which the pin is fastened really helps to hold the bouquet in place. 35

What I claim, and desire to secure by Letters Patent, is as follows:

1. A combined bouquet-holder and badge- 40 pin, wherein a curved recess for holding the bouquet or badge is made in the top bar and integral therewith, substantially as specified.

2. A combined bouquet-holder and badge- 45 pin, wherein a circular opening for holding a bouquet or badge is formed in the top bar and integral therewith, substantially as shown.

3. A combined bouquet-holder and badge- 50 pin, having an opening or hollow for holding a bouquet or badge, in connection with the top bar and points for penetrating the stems, with a pin for clasping the same and attaching it to the clothing, substantially as shown.

In witness whereof I have hereunto set my hand this 7th of July, 1882.

CHARLES P. JACOBS.
